UNITED STATES PATENT OFFICE.

CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 21,969, dated November 8, 1892.

Application filed October 10, 1892. Serial No. 448,453. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

- 10 The leading features of this design consist of scroll-shaped ornaments united near their top by a bow of ribbon, a wreath of flowers and leaves hanging from said ribbon between the ornamental scrolls, with a small spray of flowers and leaves in the center of said wreath, a vase-like ornament filled with flowers and leaves on each side of the wreath of flowers and leaves outside of the scrolls, a fleur-de-lis-shaped ornament and ribbon below the
- 15 vase of flowers and connecting the scroll ornaments, a spray of flowers hanging below

the fleur-de-lis-shaped ornament, and a festoon of flowers suspended from the top of the ornamental scrolls above the vase of flowers, as represented in the accompanying drawing. The ornamental scrolls form connecting-panels arranged side by side, and the vases of flowers and wreaths of flowers are arranged alternately in said panels.

The design is printed in any desired color or colors or in gilt and colors upon tinted paper of any desired color and is designed for a wall decoration.

What I claim is—

The design for wall-paper herein shown and described.

Witness my hand this 7th day of October, 1892.

CHARLES BOOZE.
